UNITED STATES PATENT OFFICE.

FENN H. PALMER, OF LOS ANGELES, CALIFORNIA.

ANTIREVERSING PUMP HEAD.

Application filed February 5, 1921. Serial No. 442,863.

To all whom it may concern:

Be it known that I, FENN H. PALMER, a citizen of the United States, residing at Los Angeles, in the county of Los Angeles and State of California, have invented a new and useful Antireversing Pump Head, of which the following is a specification.

This invention is applicable to the pump heads of various forms of pumps having revolving blades such as propeller pumps and centrifugal pumps.

It is customary to run pumps of this character by electric motors and gas engines, and the power is applied to a pulley fixed to the propeller shaft of the pump.

Said shaft is usually constructed of separate pieces connected together by screw threaded joints, and if the pulley is turned backward, the joints will be unscrewed thus uncoupling the shaft, and thereby causing much inconvenience and loss of life and sometimes serious breakage. It frequently occurs where a belt is twisted between the motor and pump pulleys that a workman in applying the belt will put it on wrong so that when the motor starts, the shaft is at once disjointed.

Where the power is applied to the belt by an electric motor, if the current is turned off from the motor while there is water in the pump tubing, the weight of the water on the propeller blades will cause the shaft to reverse, and this will drive the armature of the motor backward with the result that when the water has run out at the bottom of the pump tubing, the momentum of the motor armature drives the belt backward and will uncouple the shaft.

In some instances water is pumped to a considerable height by propeller pumps; and in one instance for illustration, the water in a nine-inch pump tubing was lifted sixty-five feet above the surface of the ground and discharged into a tank. The total lift from the surface of the water in the earth was about one hundred and thirty-five feet, so that when the motor stopped with that head of water resting on the propellers of the pump, the motor armature was driven backward at a high speed which uncoupled the pump shaft; and the armature continued to run for about ten minutes after the water had been discharged from the bottom of the pump.

An object of this invention is to avoid such accidental uncoupling of the shaft.

By the application of this invention reversing and uncoupling of the shaft from such causes has been made impossible.

An object of the invention is to provide a pump head with anti-reversing mechanism which will be noiseless and not subject to wear during the operation of the pump.

The invention is broadly new, basic and pioneer in that the pulley is provided with anti-reversing mechanism adapted to engage a stationary stop when the pulley is not running forward.

It is also pioneer in that a stationary ratchet is employed in connection with a revolving part of the pumping mechanism and means revolvable with the revolving part are provided to engagement to prevent reverse movement of the impeller of the pump, and is adapted to be thrown out of engagement by centrifugal force during operating speed of the impeller.

The invention is applicable with any type of rotary impeller; but illustration of the application to one type will be sufficient for a clear understanding of the invention.

Further objects, advantages and features of invention may appear from the accompanying drawing, the subjoined detail description and the appended claims.

The accompanying drawing illustrates the invention.

Figure 1 is a fragmental sectional elevation of a pump head constructed in accordance with this invention while the pulley is at rest.

Fig. 2 is a section on line x^2 , looking up, the antireversing means being shown engaged with the stationary ratchet.

Fig. 3 is a view analogous to Fig. 2 showing position of parts while the pump is being operated.

Fig. 4 is a perspective view of one of the pawls detached.

The pillar or post 1 is stationary and provided with a stationary ratchet wheel 2 which is fixed as indicated by screws S, to the top of said pillar. The pump shaft 3 is journaled by the hub 4 to revolve within the pillar 1, and is provided with a lateral projection which is shown as a flange 5 to which the web 6 of the pulley 7 is fixed by cap screws 8. The ratchet engaging means are in the form of pawls 9 pivoted to the pulley web 6 by pins 10 which are securely fixed to said web 6, each pivot being thus fixed to and revolving with the

shaft. Said pawls are normally held in ratchet engaging position by resilient means in the form of springs 11 reacting on the posts 12 to hold the pawls in the notches 5 of the stationary ratchet 2.

The springs 11 are of sufficient strength to hold the pawls 9 in engagement with the ratchet wheel 2 when the pawls are left free to be operated by the springs; but the 10 pawls are of sufficient weight to allow the centrifugal force set up therein by revolution of the pulley to throw the pawls out of engagement with the ratchet wheel.

In practice I find that with pawls weighing about 12 ounces and being set with a pivoting pin at a radial distance of four inches from the center of revolution, the operation of the pulley at 150 revolutions per 20 minute will disengage the pawls from the ratchet.

I do not limit the construction to any particular form of dimensions as it is obvious that when the principle is applied, the practical operation is very simple.

25 In Fig. 3 the belt 13 represents the power acting through the pulley 7, web 6 and web 4 to drive the shaft 3.

When the motor is started driving the belt 13 in the direction of the arrow in Fig. 30 3, the pawls are thrown out with centrifugal force into the position shown in Fig. 3, and are free from the ratchet. When the speed is reduced below that to which the springs are adapted, the pawls are returned 35 to engagement by said springs.

By extending the pawls from the pivots 10 in a direction reverse to the direction of rotation, the action of centrifugal force to 40 free the pawls from the ratchet is more directly effective.

I claim:

1. The combination with a pulley mounted to revolve; of a stationary ratchet within the periphery of said pulley, and centrifugally released ratchet engaging means carried by the pulley and adapted to be released from the ratchet by centrifugal force set up by revolution of the pulley; and yielding means to hold the ratchet engaging means in engagement with the ratchet when the pulley is at rest.

2. The combination with a pump head, of a shaft mounted to revolve; a pulley fixed to the shaft and adapted to revolve 55 the same; a stationary ratchet; and pawls carried by the pulley and adapted to engage the ratchet to prevent revolution of the pulley in one direction; said pawls being adapted to be thrown out of engagement with said ratchet when the pulley is revolved at operating speed.

3. The combination with a pump head, of a shaft mounted to revolve; a pulley

fixed to the shaft and adapted to revolve the same; a stationary ratchet; means revolving with the shaft and adapted to engage the ratchet to prevent revolution of the pulley in one direction; said means being adapted to be thrown out of engagement with said ratchet when the shaft is 65 revolved at operating speed.

4. The combination in a pump having a revolving impeller, of means to revolve the impeller, and means arranged to normal engagement to prevent reverse movement of 75 the impeller, and adapted to be thrown out of such engagement by centrifugal force at a predetermined speed of the impeller.

5. The combination with a rotary or centrifugal pump, a vertical drive shaft and 80 means for driving the shaft, of means for preventing the backward movement of the shaft comprising a clutch member which is automatically maintained out of operative engagement when the pump shaft is rotated 85 forwardly, but which automatically moves to clutching position to prevent the backward rotation of the shaft when the forward movement of the shaft is stopped.

6. The combination with a shaft, of 90 means to revolve the shaft; a pawl pivot connected to and revolving with the shaft; a pawl on said pivot; resilient means adapted to move the free end of the pawl toward the center of revolution; and a stationary 95 ratchet wheel arranged to be engaged by the pawl upon its approach toward the center of revolution, said free end of the pawl being thrown out from said stationary ratchet and released therefrom by centrifugal force as the shaft speeds up.

7. The combination with a shaft, of 100 means to revolve the shaft; a pawl pivot connected to and revolving with the shaft; a pawl on said pivot and having its free end extending reverse to the direction of rotation of the shaft; resilient means adapted 105 to move the free end of the pawl toward the center of revolution; and a stationary ratchet wheel arranged to be engaged by the pawl upon its approach toward the center of revolution, said free end of the pawl being thrown out from said stationary ratchet and released therefrom by centrifugal force as the shaft speeds up.

8. In a rotary pump a vertical line shaft, a housing therefor, and a ratchet secured to the housing, in combination with a centrifugal pawl mounted on the line shaft and adapted to swing into contact and out of contact with the ratchet according as the line shaft stops or rotates.

In testimony whereof, I have hereunto set my hand at Los Angeles, California, this 24th day of December, 1920.

FENN H. PALMER.
